UNITED STATES PATENT OFFICE

JOHN M. CARTER, OF ORLANDO, FLORIDA

JOINT OR CONNECTER FOR ROOFING SHEETS

Application filed November 29, 1930. Serial No. 499,085.

This invention relates to sheet metal building construction and particularly to means for joining or connecting the edges of metal sheets, particularly of corrugated roofing. 5 The general object of this invention is to provide a joint or connector between the edges of two metal sheets of corrugated roofing of such character that the joint will be water-proof and that it will eliminate the 10 waste caused by lapping.

A further object is to provide a connection which will prevent snow or rain from blowing under the roofing along the lap.

A further object is to save time and labor 15 in forming the corrugated roof and provide a connector which will aid or guide the workman in keeping the joints in straight lines, thus adding to the appearance of the roof or siding.

20 My invention is illustrated in the accompanying drawings, wherein:—

Figure 1 is a top plan view of a plurality of roofing sheets or connecting elements or joints engaged therewith in accordance with my 25 invention;

Figure 2 is a section on the line 2—2 of Figure 1;

Figure 3 is a like view to Figure 2 but showing a variation in the cross section;

30 Figure 4 is a top plan view of the two sections or connectors telescoped;

Figure 5 is a section on the line 5—5 of Figure 4;

Figure 6 is a transverse section through a 35 connector showing one means whereby it may be connected to a metal purlin;

Figure 7 is a section on the line 7—7 of Figure 6.

In Figure 2, A and B are two corrugated 40 sheets of metal such as are ordinarily used for roofing or siding. Such sheets as this are usually overlapped at the joint for about 1½ corrugations. Such a joint as this is not completely water-proof and water might pass 45 along said joint by capillary attraction and so that water will penetrate beneath the roof. Furthermore, this overlapping of the sheets is wasteful. To avoid this, I provide a connector or joint designated generally 10 having a medially disposed, approximately cir-

cular bead 11. This bead is nearly closed at 12. The metal on each side of this bead is carried laterally from the contracted portion 12 outward in opposite directions as at 13 and then extended upward, downward and inward as at 14 so as to form what may be termed lateral beads. The side edges of the sheets A and B are forced down over these lateral beads and underneath the medial bead 11 so that the edges of the sheets A and B will engage the medial bead at the neck 12.

Of course, the upper edge of each sheet A or B is disposed beneath the overlap of an upper sheet and the lower edge of each sheet A or B is overlapped upon the sheet below. As illustrated in Figure 1, the joint 10 at its ends has extensions 15 forming the extensions of the flat portions 13 of the lateral bead which are apertured for the passage of nails where this device is to be applied upon a wooden building. These joint or connecting members 10 are designed to have any desired standard length to correspond with the lengths of the metal sheets. Thus these joint or connecting members may have 70 lengths of four, five, six, seven, eight, nine and twelve feet.

Where it is necessary to join one connector 10 with an adjacent connector, two connectors are telescoped into each other as illustrated in Figure 4. In this case, the bead 11 of one connector receives within it the bead 11 of the next connector below, but preferably the lateral beads of the upper connector will be inserted in the lateral beads of the 80 lower connector. This is illustrated in Figure 4. Where this connector or joint is to be used on frame buildings, it is formed, as before stated, with the outwardly projecting lugs 15 by which it may be nailed to the 85 sheathing of the building or to the joists. Where this connector is to be used on a metal frame building, two bolts 16 are disposed, one on each side of the purlin or other structural element, each of these bolts having an 90 enlarged head 17. The bead 11 is then slipped on to these bolts so that the shank of the bolt extends through the neck 12 and the head of the bolt is disposed within the bead 11. Thus these bolts hold the connector in 95 100

place. Obviously the bolts may be connected to the metal framing of the building in any desired manner, provided the heads of the bolts are so formed as to fit within the bead 11.

While I have illustrated in Figure 2 a connector 10 which is formed with an approximately circular bead 11 and with somewhat elliptical lateral beads, I do not wish to be limited to this. In Figure 3, I show a connector designated 10^a which is exactly like the connector 10 except that the lateral beads are approximately triangular in cross section instead of being approximately ovoid in cross section.

In Figure 6, I illustrate a connector 10^b in which the medial bead 11^b is approximately triangular in cross section. It will thus be seen that the exact form of the connector in cross section may be varied widely without departing from the spirit of the invention as defined in the appended claims.

The connector constructed in accordance with my invention not only makes a waterproof joint between two adjacent sheets and eliminates the waste caused by overlapping of the sheets, but such a joint aids or guides the roofer in keeping the joints in a straight line, thus adding very greatly to the appearance of the roof or siding. The joint illustrated will hold the edges of the corrugated sheets in proper position at all times and the lateral bead constitutes ducts whereby any water which may enter the joint will be carried downward and be discharged at the eaves with no chance of the water entering the joint and collecting between the sheets and the sheathing of the roof.

It is very essential that the connector 10^a or 10^b shall have a flat base with means to fasten the connector securely to the sheathing boards to prevent the connector from being turned up on either edge by wind getting under the roofing sheets and thus lifting one bead or lateral channel higher than the other, causing an overflow of water. It is also particularly necessary that the margins of the lateral beads be extended downward and inward so as to secure a good contact with the downwardly and inwardly extending margins of the lateral sheets, as shown most clearly in Figures 2 and 3, the margins of the sheets A and B being extended downward and inward, preventing water being blown out of the channel during a heavy rain and wind storm, which produces whirling motion in the channels. The margins of the beads being extended inward and downward forces water back toward the neck of the connector and out at the ends. If the margins of the lateral beads terminated perpendicularly against the roofing sheets or the margins of the lateral beads do not extend downward and inward and conform to the lateral margins of the roofing sheets, a whirling motion

of the water in the channels forces water upward and outward between the margin and the roofing sheets, thus causing the water to go inside of the building instead of out through the channels.

A further object in extending the lateral margins of the beads inward and downward is to close the openings at the tops of the channels, which prevents the channels getting clogged. The margins of the roofing sheets being extended inward over the tops of the lateral beads holds the roofing sheets securely and forces upward on the edges of the roofing sheets, forcing them against the bottom of the central bead. The pressure is uniform for the entire length of the roofing sheet and prevents rattling.

While I have illustrated my joint as applied to a corrugated metal roof or siding, I do not wish to be limited to this as flat sheets might be used in place of corrugated sheets provided the lateral edges of the sheets are upwardly and then downwardly bent so as to extend down over the lateral beads of the joint and into position on each side of the metal bead of the joint.

I claim:—

1. A connector for roofing sheets formed to provide a medial upstanding bead and two integral lateral beads extending laterally in opposite directions from the base of the medial bead and having upwardly and then inwardly turned marginal portions.

2. A joint or connector for roofing sheets formed of a single strip of sheet metal, the strip being bent to form a medial upstanding bead, the metal on each side of the neck of the bead being laterally extended to rest upon the sheathing of the building, then upwardly, inwardly and downwardly extended to form lateral beads.

3. The combination with parallel corrugated sheets of metal, of a connector formed of a strip of metal bent to form a medial upstanding bead, the metal at the neck of said bead being laterally bent in opposite directions to lie against the building sheathing and then extended upward, inward and downward toward said neck, the margins of the corrugated sheets being inserted between said lateral beads and the medial bead with the edges approximating the neck of the medial bead and the material outward of said edges bearing against the upper faces of the lateral beads.

4. In a building, a building element, covering sheets therefor, a connector between said covering sheets formed to provide a medial portion and lateral beads, the medial upstanding portion overhanging the lateral beads and having a contracted neck, the adjacent margins of the sheets being inserted between the medial portion and lateral beads and bearing against the upper faces of the lateral beads and bolts engaging with said building element and having heads disposed

within the medial portion, the shanks of the bolts extending through the neck at the junction of the medial portion with the lateral beads.

- 5 5. The combination with parallel corrugated sheets of metal, of a connector formed of a strip of metal bent to form a medial upstanding portion having a neck, the metal at the neck of said medial portion being laterally bent in opposite directions to lie against the building sheathing and then extended upward, inward and downward toward said neck, the margins of the corrugated sheets being inserted between said lateral beads and
- 10 15 the medial portion with the edges approximating the neck of the medial bead, the strip being formed to provide longitudinally extending lugs whereby it may be attached to the sheathing of the building.
- 20 25 6. A joint or connector for roofing sheets formed to provide a medial upstanding portion having a contracted neck and two integral and lateral beads having approximately flat lower surfaces extending laterally from the neck to lie against the sheathing of the building, then extending upward, inward and downward toward the neck of the medial portion.
- 30 35 7. The combination with two roofing sheets having their adjacent margins upwardly and then downwardly curved, of a connector for forming a joint between the two sheets comprising a strip of metal formed to provide a medial upstanding portion having a contracted neck, the metal at the neck of said medial portion being extended laterally and then extending upwardly, inwardly and downwardly to form lateral beads, the margins of the metal sheets being inserted between the medial portion and the lateral beads and bearing against the upper surfaces of the lateral beads and at their inner edges bearing against the under surface of the medial portion.
- 40 45 8. In combination with roofing or siding sheets having their adjacent ends upwardly and then downwardly curved, of a plurality of connectors, each connector being formed of a strip of metal formed to provide a medial upstanding portion having a constricted neck, the metal on each side of the neck being laterally extended and then extended upward, inward and downward, the curved margins of the sheets being disposed over the lateral beads so formed and inserted in the lateral beads and the under surface of the medial portion, successive connectors having their medial portions and lateral beads telescoped.
- 50 55

In testimony whereof I hereunto affix my signature.

JOHN M. CARTER.
